(57) **CLAIM**

The ornamental design for a shovel blade, as shown and described.

DESCRIPTION

FIG. 1 is a top front perspective view of the shovel blade of the instant invention;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portions of the figures illustrated in broken lines are for illustrating surface contours only and form no part of the claimed design.

The dashed lines on the shovel head represent soft contour lines which form part of the claimed design. The broken lines on the shovel handle represent portions of the article and form no part of the claimed design.
